CROSS-HEAD FOR INHIBITOR EXTRUSION
Emery J. Bowers, China Lake, and Rodney D. Sutherland,
Pomona, Calif., assignors to the United States of
America as represented by the Secretary of the Navy
Filed May 24, 1960, Ser. No. 31,490
4 Claims. (Cl. 18—13)
(Granted under Title 35, U.S. Code (1952), sec. 266)

The invention described herein may be manufactured and used by or for the Government of the United States of America for governmental purposes without the payment of any royalties thereon or therefor.

This application is a continuation-in-part of application Serial No. 650,542, now abandoned.

This invention relates to improvements in coating devices, and more specifically to cross-head means for continuously coating rod-like articles by depositing a coating of material on such articles continuously as the articles are drawn through the cross-head.

Devices of the general nature of the cross-head means which is the subject of the present invention are old and well known in the art. It has been common practice to coat a rod or wire with coating or insulating material by drawing the rod or wire through an enclosing mandrel to a zone wherein coating material under pressure is forced about the rod or wire as it emerges from the mandrel and to feed the coated article through a die to thereby control the thickness of the coating as well as the outer diameter of the coated article. However, these prior devices have certain disadvantages which result in imperfect coatings and especially where great accuracy is required. One of the primary disadvantages of the prior art devices is that the coating had a pronounced tendency to neck down or taper at the ends of short articles fed through cross-heads of the general type herein discussed. In addition, prior art devices have not been adequate for the application of coating material to propellant grains because of the unique problems involved.

In order to apply viscous thermoplastic coating materials to propellant grains, it is necessary to heat the coating material to a predetermined temperature to assure proper flow and bonding characteristics. Steam passages are provided in the cross-head and die to maintain the coating material at the proper temperature. However, since the propellant grain is slowly transmitted through the cross-head and die, the grain is heated which results in reduced bending strength and increased surface friction coefficient. Since the friction coefficient of the grain is increased, it is necessary to provide minimum surface contact between the grain and the mandrel so that minimum frictional drag is obtained. In addition, since the propellant grain is fed to the mandrel by an external roller conveyer system, it is necessary that the mandrel have an external opening which is greater than the diameter of the grain to compensate for misalignment between the conveyed propellant grain and the opening in the mandrel.

The method by which minimum surface contact is obtained and the mandrel external opening is of sufficient size to compensate for misalignment, is by continuously tapering the mandrel passage from a first diameter, which is approximately the same size as the propellant grain, to second diameter, which is somewhat larger than the first diameter. The first diameter section is adjacent the die, wherein the coating is applied to the grain, and is the section which supports the largest weight of the propellant grain. The second diameter section is adjacent the conveyer system and provides sufficient tolerance to compensate for misalignment.

As previously noted, the propellant grain is heated,

2

which results in reduced bending strength and as a consequence the propellant grain bends, as a result of its weight, within the mandrel and is in contact with the lower surface of the taper. It is critical that the permitted propellant grain bend, which is determined by the length and taper of the mandrel, does not exceed the point where permanent set would be introduced into the grain since the grain, as finally coated, would not be longitudinally aligned.

Therefore, the present invention provides a mandrel that has a tapered opening extending the entire length of the mandrel. The primary function of the taper is twofold: (1) It provides a minimum diameter and a corresponding minimum surface contact at the end adjacent the die. This permits the propellant grain to be laterally moved within the mandrel with minimum force applied thereto. (2) It provides a maximum diameter at the end adjacent the conveyer system. This compensates for misalignment of the feed of the conveyer system. However, the taper is such that permanent set will not be introduced into the heated propellant grain.

An additional function of the taper is the provision of an air space between the grain and mandrel surface. This air space reduces the heat transfer from the mandrel to the grain which is highly desirable since reduced grain temperature results in reduced frictional coefficient and increased bending strength. It should be noted that the size of mandrel opening adjacent the conveyer, may be increased or decreased by changing the length of the mandrel. The maximum length is limited; however, since if too long, the propellant grain would be within the mandrel for too great a time and would heat to its critical temperature. The minimum mandrel length is determined by the size of opening adjacent the conveyer which is necessary to compensate for the particular alignment characteristics of the conveyer employed.

Another unique feature of the present invention is the provision of means for cooling the propellant grain should the grain become stationary within the mandrel. If the grain were to become stationary within the mandrel, for any of a plurality of failure reasons, the heat of the crosshead, die and mandrel would be transmitted to the grain which would result in increasing the grain temperature to the ignition point with corresponding explosion. This is the case even though the heating steam is turned off as soon as the grain becomes stationary. In order to prevent the explosion of the grain, cooling liquid is transmitted through the steam cavities as soon as the grain becomes stationary. A solenoid device is employed which shuts off the steam and turns on the cooling liquid upon the actuation of a single mechanism.

The present novel extrusion coating cross-head overcomes the prior art difficulty of tapering the coating at the ends of articles being coated. While this tendency of prior art devices is relatively unimportant in coating long articles since a small tapered end can be cut off without great relative loss, it becomes important when short individually separated articles are fed through such cross-heads for coating. The novel crosshead which is the subject matter of this invention includes a land which is attached to the die and serves to outline the die opening size, the land being of a specially critical thickness which has been found to inhibit the tendency of the coating material to taper at the ends of the articles being coated. It has been found that if the land thickness is too small, there are resulting pulsations or ripples in the coated surface. If the land thickness is too great there is a resulting excessive necking down or taper at the end of the individual grain. The exact reasons for these characteristics are not known; however, it is believed that when the land thickness is too great, there is increased land drag which forces the coating material off the end of

the grain. The critical thickness is that land thickness which results in a smooth coating surface and minimum necking. It has been found, for use with viscous thermoplastic materials, that a land thickness of approximately $\frac{1}{4}$ inch is critical.

Other features of the present invention include: (1) means for easily and accurately adjusting the relative longitudinal position of the mandrel with relation to the die to closely control the volume flow of the coating material, (2) off-setting the die with relation to the mandrel to provide a coating of uniform thickness and (3) means for accurately and easily reproducing the position of the die with relation to the cross-head.

It is, therefore, an object of this invention to provide new and improved apparatus for the continuous extrusion of coating material on the external surfaces of pipe or rod-like articles.

A further object of this invention is to provide continuous extrusion type coating means wherein the tendency to thinning of the coating at the ends of articles to be coated is minimized and the coating has a smooth surface.

A further object of this invention is to provide continuous extrusion type coating means which is fed propellant grains by a conveyer means wherein the mandrel compensates for conveyer misalignment and prevents permanent set from being induced in the propellant grains.

A further object of this invention is to provide a continuous extrusion type coating means for propellant grains wherein the propellant grains are insulated from the mandrel by an air space.

A further object of this invention is to render it necessary to provide only a small force to move the propellant grain longitudinally through the mandrel.

A further object of this invention is to provide continuous extrusion type coating means wherein the mandrel has a continuously tapering opening extending the entire length of the mandrel.

A still further object of this invention is to provide a continuous extrusion type coating means for propellant grains which prevents overheating of the propellant grain when the grain becomes stationary within the extrusion coating means.

A still further object of this invention is to provide a continuous extrusion cross-head type coating means wherein coating thickness is closely and reproducibly controllable by easily resettable positioning of the mandrel through which articles to be coated are fed into the coating zone of the cross-head.

Yet another object of the present invention is to provide extrusion cross-head type coating devices having easily resettable means for adjusting the outlet die eccentrically of the longitudinal axis whereby concentric coatings may be obtained despite pressure differentials within the coating zone of the cross-head.

Still another object of this invention is the provision of extrusion coating cross-head means for precisely forming relatively thin, concentric coatings of burning inhibiting plastic material on the external surfaces of solid propellant rocket grains.

These and other objects and many of the attendant advantages of the present invention will become apparent as the same becomes better understood from the following detailed description taken in conjunction with the accompanying drawings wherein:

FIG. 1 is a sectional view through an extrusion coating cross-head according to the present invention, being taken along the line 1-1 of FIG. 2;

FIG. 2 is a view taken along the line 2-2 of FIG. 1, in the direction of the arrows, with the article to be coated removed and with portions broken away to show the orientation and operation of the die eccentricity indicating devices at the outlet end of the extrusion coating cross-head; and

FIG. 3 is a view, partially in section, of the inlet end

of the crosshead of FIG. 1 with the article to be coated removed, being taken along the line 3-3 of FIG. 1, in the direction of the arrows.

Referring now to the drawings, wherein like reference numerals have been appended to like parts throughout, attention is first directed to FIG. 1 for a description of the general nature of the type of device with which the present invention is concerned. In devices of this type, articles A, to be coated, are fed by means of conveyer B through an encompassing mandrel C to a coating zone D where the articles emerge from the mandrel to be coated by material fed under pressure through an inlet passage E, the coated articles then moving through a die F which shapes and controls the size of the coated articles.

In the specific embodiment of such devices which forms the subject matter of the present invention a cross-head casing 2 is supported (by means not shown) in sealed relationship with inlet passage D serving as a source of supply of coating material. The casing 2 is open at both ends to provide a longitudinal chamber having a cylindrical portion at one end serving to closely accommodate the after or entry end of the mandrel C and an enlarged chamber D at the other end to provide a coating zone around the forward end of the mandrel, the chamber or zone C being in communication with inlet passage E.

The mandrel C is adjustably positioned within the cross-head casing 2 by means of a mandrel retainer body 4 in the form of an annulus fixedly positioned on the after end of cross-head casing 2, as by screws 6. The retainer body is cut away internally at its after end to provide an annular ledge 8. The ledge 8 is provided with an anti-friction bearing ring 10 (of a material such as Teflon) to serve as a support and bearing for the mandrel adjustment ring 12. The mandrel adjustment ring 12 is of generally annular form, having a stepped outer diameter having a smaller portion 13 of a diameter to be rotatably and slidably accommodated within the retainer body 4 and having a larger diameter 14 adapted to be engaged by the shoulder 8 of the retainer body 4 for rotation on the bearing ring 10. The larger diameter 14 has an annular notch therein for accommodating the radially inner edge of a split annular retainer ring 16. Retainer ring 16, engaging the notch in the mandrel adjustment ring 12, is attached by a plurality of cap screws 17, to the after end of the mandrel retainer body 4, as best shown in FIG. 1.

By virtue of the arrangement described above, the retainer ring 12 is capable of rotary motion about the longitudinal axis of the cross-head while being restrained against longitudinal motion. Retainer ring 12 is internally screw-threaded as at 18 for cooperation with mating screw threads 20 on the after end of the mandrel C whereby rotation of the ring (with the mandrel fixed against rotary motion) is effective to adjust the longitudinal position of the mandrel in the cross-head. Mandrel C has an attached key element 22 which rides in a key slot 24 in the casing 2 to prevent rotary motion of the mandrel. Thus, the mandrel C, extends longitudinally of the cross-head, to the general vicinity of the coating zone D and is adjustable relative to the die by rotation of the ring 12 to vary the feed characteristics of the coating. The ring 12 is provided with openings 25 for cooperation with a spanner-type wrench for adjustment and is provided with indicia (not shown) to be aligned with indicia, as for example an arrow 58 on the retainer ring 16 to give a vernier type reading of mandrel adjustment.

As best depicted in FIG. 1, mandrel C has a continuously tapered cavity 27 extending the entire length thereof. At the end adjacent die F, the diameter of the tapered cavity is approximately the same as the diameter of the propellant grain. At the other end of the tapered cavity, adjacent conveyer B, the diameter is larger than the propellant grain. The propellant grain is heated in the cavity and as a result the frictional coefficient of the

surface is increased and the bending strength is decreased. Therefore the propellant grain will bend and contact the lower internal surface of the mandrel. The taper is such that the propellant grain will not bend to the extent where permanent set is induced therein. It has been found that a taper of approximately $\frac{1}{8}$ inch per foot prevents permanent set from being induced in propellant grains of the type employed. The diameter of the tapered cavity at the end adjacent conveyor B is determined by the taper length of the mandrel and is selected to compensate for maximum conveyor misalignment. It should alone be noted that the greatest weight of propellant grain is located at a relatively small surface area near the end of the mandrel adjacent the die which minimizes the force necessary to propel the grain through the mandrel cavity.

The die F is positioned on the forward end of the cross-head by means of an adapter plate 26 which is suitably attached to the cross-head casing, as by a plurality of screws 28, as shown. Adapter plate 26 is in the form of an annulus having an inwardly directed flange 30 defining an opening of somewhat greater size than the coated articles to be handled and providing an internal chamber 32 of a depth of longitudinally position the die F between the forward wall of the cross-head casing and said flange 30. The chamber 32 is of inner circumference which is somewhat greater than the outer circumference of the die F whereby a slight degree of transverse motion of the die may be effected, relative to the longitudinal axis of the cross-head. The chamber size and thus the degree of possible lateral motion of the die are further determined by the provision of a ledge 34 formed on the forward edge of the cross-head casing 2, the ledge providing a bearing and support for the after end of the die and the side wall thereof, aligned with the inner wall of chamber 32 serving to limit lateral movement of the die.

Means are provided for adjusting the concentricity or eccentricity of the die F relative to the mandrel and cross-head casing and for indicating said relative position, the best showing of such means being in FIG. 2 of the drawing. The adapter plate is provided, a four equiangularly disposed points with screw-threaded radial bores in which externally and internally threaded bushings 36 are inserted, as shown in FIG. 2. Adjustment screws 38 are threaded through bushings 36 and are of a length to contact the periphery of the die F as at 40 whereby adjustment of the eccentricity of the die F may be effected by the settings of said screws 38.

Means are also provided for accurately indicating a given position of the die F so that it may be reproduced without resorting to trial and error methods. Such means comprise a pair of displacement indicators 42 held in opposed equally off-center positions relative to the die by means of a bracket support 44 suitably attached to the casing 2 by screw means not shown. The bracket and casing have aligned radial bores in which bushings 46 are positioned to permit passage of the sensing arms 48 of the indicators 42 through the bushings into contact with the outer periphery of the die F. Thus, as may be readily seen in FIG. 2 of the drawings, the set screws 38 may be adjusted to control the lateral adjustment of the die F, the readings on the indicators 42 indicating the adjusted position. It is therefore possible to reset the die (after cleaning or change of materials) to a desired, reproducible position by adjusting the known desired indicator readings.

Attention is now directed to the construction of the die F. It has been discovered, as a related important factor in extrusion formation of external coatings, that the tendency of coatings to be free from tapered thickness at the ends of the articles being coated may be controlled by the longitudinal thickness of the wall of the die portion through which the coated article finally passes in the formation of its outer diameter. It is common, in

this art, to provide a die with a portion, generally termed a "land", to define the peripheral outline of the extruded article and the land may be either an integral part of the die or a detachable element. In the illustrative example, as depicted best in FIG. 1, the land 50 is formed as an integral piece of an externally screw-threaded annulus 52 which is threaded into the forward portion of the die body as shown, such an arrangement allowing interchangeable use of different size lands. It has been found, for use with viscous thermoplastic materials, that a land thickness of approximately $\frac{1}{4}$ inch is critical and results in substantially overcoming the tendency for tapering of the coating and provides a smooth uniform coating. It has been found that a land having a thickness greater than $\frac{1}{4}$ inch, $\frac{1}{2}$ inch for example, results in a taper that is too great and consequently unsatisfactory. Whereas a land having a thickness less than $\frac{1}{4}$ inch, $\frac{1}{8}$ inch for example, results in a pulsating or rippling surface which is likewise unsatisfactory.

Passages 56 are provided in the cross-head casing 2, and similar passages 54 are provided in the die F whereby hot fluids, steam for example, may be circulated about the areas through which coating fluids pass, in order to maintain proper condition of such fluids when thermoplastics are used.

In operation, articles to be externally coated are fed by means of conveyor B, shown in broken lines for simplicity, into the enlarged aft end of the cross-head through the large tapered portion of mandrel C, and coating material is fed under pressure through the lateral inlet F to the coating zone D, and maintained at ideal coating temperatures by fluids passing through passages 54 and 56. The article is pushed through the mandrel and coating zone past the die F, which has an opening larger than the article, as defined by the land 50 and the result is an extrusion of a coating of material about the article. The feed characteristics of the coating may be accurately preset by rotation of the adjustment ring 12 which controls the longitudinal position of the mandrel C, to a desired position as indicated by indicia on the ring 12 and on retainer ring 16. Moreover, the arrangement is such that adjustments may be made, if desired, while the device is in operation. As mentioned hereinabove, it has been discovered that the concentricity of the coating requires an eccentric positioning of the die F relative to the mandrel and screws 38 are adjustable to provide such eccentricity, the displacement indicators 42 serving to give reproducible evidence of the proper position of die F for a given set of conditions.

If for some reason the propellant grain should become stationary within the mandrel, a cooling medium, cold water for example, is provided to prevent the heat of the cross-head, die and mandrel from being transmitted to the propellant grain which would result in increasing the grain temperature to the ignition point with corresponding explosion. When the grain becomes stationary, valve actuating device 62 is actuated in a direction that causes an output signal to be applied to solenoid 64 to open valve 66 and an output signal to be applied to solenoid 68 to shut off valve 70. In this manner heating steam is shut off and cold water is forced through passages 54 and 56 which absorbs the heat of the cross-head, die and mandrel thereby preventing the transmission of excessive heat to the propellant grain.

In order to provide automatic control, propellant grain motion responsive device 72 senses whether or not the grain is in motion. When in motion, the output signal from device 72 is applied to the input of valve actuating device 62 which opens valve 70 and closes valve 66. However, when the grains become stationary, the output signal from device 72 causes actuating device 62 to close valve 70 and open valve 66. An override switch 74 is provided to disconnect motion responsive device 72 so that the operation of valve actuating device 62 may be manual.

Obviously, many variations and modifications of the present invention are possible in the light of the above teachings. It is therefore to be understood that the scope of the invention is to be restricted only by the scope and limitations of the appended claims and not by the details of the single illustrative example specifically described hereinabove.

What is claimed is:

1. An extrusion type coating device of the type wherein the articles to be coated will ignite at a predetermined temperature and the articles to be coated are passed through a mandrel having an opening and into a coating chamber which is connected to a source of coating material and first means for heating said coating material and mandrel the improvement comprising second means for cooling said coating material and mandrel, means responsive to the motion of said articles for rendering said first means operative when said articles are moving through said mandrel and rendering said second means operative when said articles are stationary in said mandrel, thereby preventing said articles from reaching said predetermined temperature.

2. An extrusion coating device wherein the articles to be coated will ignite at a predetermined temperature comprising a cross-head casing having passages therein, a mandrel disposed in said cross-head casing and having an opening therein for receiving said articles, a die having passages therein and connected to said cross-head casing and disposed adjacent one end of said mandrel, a chamber formed between said die and mandrel, a source of coating material in communication with said chamber, a source of heating medium, a source of cooling medium, and means responsive to the motion of said articles for connecting said heating medium to said passages when said articles are moving through said mandrel and connecting said cooling medium to said passages when said articles are stationary in said mandrel thereby preventing said articles from reaching said predetermined temperature.

3. An extrusion coating device wherein propellant grains to be coated will ignite at a predetermined temperature comprising a cross-head casing having passages therein, a mandrel disposed in said cross-head casing and having an opening therein for receiving said propellant grains, a die having passages therein and connected to said cross-head casing and disposed adjacent one end of said mandrel, a chamber formed between said die and mandrel, a source of coating material in communication with said chamber, a source of hot fluid, a source of cold fluid, a first conduit interconnecting said source of hot fluid and said passages, a first valve in said first conduit, a second conduit interconnecting said source of cold fluid and said passages, a second valve in said second conduit,

5

means responsive to the motion of said propellant grains for simultaneously opening said first valve and closing said second valve when said propellant grains are moving through said mandrel, said means simultaneously closing said first valve and opening said second valve when said propellant grains are stationary in said mandrel thereby preventing said propellant grains from reaching said predetermined temperature.

10

4. An extrusion coating device wherein the propellant grains to be coated will ignite at a predetermined temperature and the bending strength of the grains decrease with increasing temperature comprising a cross-head casing having passages therein, a mandrel disposed in said cross-head casing and having an opening extending the entire length thereof, a die having passages therein and connected to said cross-head casing and disposed adjacent one end of said mandrel forming a chamber between said die and said mandrel, means for feeding said propellant grain through the opening at the other end of said mandrel, a source of viscous thermoplastic material communicating with said chamber, said die having a radially inwardly directed land defining the external outline of the coated articles, said land having a thickness in the order of $\frac{1}{4}$ inch whereby the coated surface is smooth and there is minimum necking down of the coating at the end of the coated grains, said opening of said mandrel being continuously tapered by increasing diameter from said one end to said other end, said taper being approximately $\frac{1}{8}$ inch per foot thereby preventing permanent set from being induced in said propellant grain when it is heated and bent in contact with the lower surface of said tapered opening, a source of heating medium, a source of cooling medium, means responsive to the motion of said grains for connecting said heating medium to said passages when said propellant grains are moving through said mandrel and connecting said cooling medium to said passages when said propellant grains are stationary in said mandrel thereby preventing said propellant grains from reaching said predetermined temperature.
